(57) **CLAIM**

The ornamental design for a bin, as shown and described.

DESCRIPTION

FIG. 1 is a top, left perspective view of our new design for a bin.

FIG. 2 is a front elevation view of FIG. 1.

FIG. 3 is a back side elevation view of FIG. 1.

FIG. 4 is a right side elevation view of FIG. 1.

FIG. 5 is a left side elevation view of FIG. 1.

FIG. 6 is a top plan view of FIG. 1.

FIG. 7 is a top, left perspective view of a second embodiment for a bin, showing our new design;

FIG. 8 is a front elevation view of FIG. 7.

FIG. 9 is a back side elevation view of FIG. 7.

FIG. 10 is a right side elevation view of FIG. 7.

FIG. 11 is a left side elevation view of FIG. 7; and,

FIG. 12 is a top plan view of FIG. 7.

The broken lines are included to show portions of the bin, which form no part of the claimed design.
